VAPOR LIQUID SOLVENT EXTRACTION
PROCESS

Henry J. Hibshman, Plainfield, and Robert H. Lafferty, Bradley Beach, N. J., assignors to Standard Oil Development Company, a corporation of Delaware

Application October 11, 1944, Serial No. 558,260

4 Claims. (Cl. 202—39.5)

1

This invention relates to the solvent treatment of mineral oil and especially to the recovery of the solvent from an overhead vapor when vapor-liquid extracting a petroleum fraction using a solvent having a boiling range within about 150° F. of the boiling range of the mineral oil being extracted.

In the treatment of mineral oils it is common to concentrate desirable constituents or remove undesirable impurities from the oil by the use of various selective solvents. It has been common to use either of two methods for accomplishing the extraction. In the first, the liquid oil is treated countercurrently with a liquid solvent to produce a raffinate rich in the more paraffinic constituents and containing relatively small amounts of solvent, and an extract phase containing the more aromatic constituents dissolved in a relatively large amount of solvent. In this process as normally carried out on lubricating oils, the boiling point of the solvent is usually at least 200 or 300° F. lower than the petroleum fraction being treated and is easily removed from the extract and raffinate by distillation. The extraction of lubricating oils using phenol, furfural and chlorex are examples of such extractions.

The second process for the treatment of petroleum fractions with selective solvents involves introduction of the liquid solvent into one end of a treating system into the center of which the petroleum fraction is introduced, usually in a wholly or partially vaporized state. The petroleum vapor passes countercurrently to the solvent. The more aromatic or hydrogen-deficient constituents are concentrated in the liquid solvent phase while the more paraffinic or hydrogen-rich constituents are concentrated in the vapor phase. A portion of the hydrocarbons dissolved in the solvent is revaporized at the extract end of the unit to produce hydrocarbon vapors in this section of the unit thereby effecting further purification of the aromatic constituents. Since in such a process it is common to use solvents boiling within about 200° F. of the boiling range of the petroleum fraction being treated, the raffinate phase usually contains a considerable quantity of solvent which is often relatively difficult or impossible to remove by simple distillation. Examples of this second procedure for solvent extracting petroleum fractions are as follows: (1) the extraction of toluene from virgin cracked and hydroformed naphthas using solvents such as phenol, methyl ethyl ketone, and methyl alcohol, and (2) the extraction of isoprene and n-butyl-
enes using acetone as a selective solvent.

2

The recovery of solvent from the products of this second method of solvent treating petroleum fractions is the subject of this patent application. It has been found that the solvent loss in the extractor overhead can be appreciably reduced by the injection into the top of the extractor of relatively small quantities of a second solvent which is completely or at least partially miscible with the first solvent but relatively insoluble in the petroleum fraction being treated. In the preferred method of recovering solvent, the secondary solvent boils from 25 to 200° F. lower than the petroleum fraction being treated. In this case the secondary solvent is revaporized in the raffinate end of the treating zone and appears with the raffinate from which it is separated by decantation and recycled to the treating zone. It has been found that when operating in this manner the solvent loss with the raffinate is reduced to from $\frac{1}{2}$ to $\frac{1}{4}$ the loss without injecting a secondary solvent.

As an example of this process, it has been found that when vapor liquid extracting toluene from a 175-250° F. boiling range, hydroformed naphtha containing 21% toluene using phenol in the ratio of 300 parts phenol to 100 parts naphtha feed and a reflux ratio of 1/1 with 10 plates above the phenol feed point, that the raffinate contains 1.5# phenol/bbl. of raffinate. When 9 vol. percent water is injected into the top of the extraction tower while using only a 1/3 reflux ratio, the phenol content of the raffinate is reduced to 0.2# phenol/bbl. of raffinate.

More generally, about 6 to 12 volume percent of water may be employed in toluene extraction processes of this character. In the case in which phenol is employed for the vapor liquid extraction of xylenes, the amount of water employed is about 25-41 volume percent based upon the volume of hydrocarbons withdrawn as an overhead product. The specified amount of water is the quantity required to form constant boiling mixtures between the water and the overhead hydrocarbon products.

This invention will be more clearly understood on reading the following description with reference to the attached drawing. Reference numeral 1 designates an extraction tower provided with perforated plates 2 and a steam coil 3 in the bottom to regulate the temperature. The naphtha to be extracted is introduced by means of pipe 4 to the center of the extraction section, below the point where the primary solvent is injected. The naphtha is introduced into the tower in the vapor state. Phenol, liquid phenol in this case, is in-

troduced about one-third down from the top of the tower through pipe 5 and flows in counter-current flow to vapors of the naphtha rising upwardly through the tower. It is not intended to limit this invention to the extraction of toluene and xylene or to specify the solvent named as other mixtures may be extracted with the use of other solvents such as cresols methylethyl ketone, furfrol, acetone, etc. Phenol flowing downwardly through the tower is separated with dissolved ingredients by means of solvent recovery pipe 6 provided with valve 7. The vapors rising upwardly through the tower are removed by means of pipe 8 and passed through condenser 9. A condensate passes through pipe 10 to settler 11 where a separation of the mineral oil from water which is also present is obtained. A raffinate oil may be passed by means of pipe 12 provided with valve 13 to the upper part of the tower as a reflux to effect more efficient separation of the mixture. The remaining part of the raffinate that is not used as a reflux is removed through pipe 14 provided with valve 15. The water is removed from the settler 11 by means of pipe 16, provided with valve 17, and is returned to the upper plates of the extraction tower. The plates upon which this water is refluxed are the upper plates preferably the top plate along with the refluxed oil. However, it is permissible to introduce the water on or even below the phenol feed plate. The excess water may be removed by means of pipe 18 provided with valve 19 and if sufficient water is not present, fresh water may be introduced by means of this pipe 18. The water which was removed through pipe 8 was vaporized within the column and in so doing condensed an amount of hydrocarbon proportional to the respective heats of vaporization (vaporization of 1 liquid volume of water serves to condense about 10 liquid volumes of hydrocarbon).

The quantity of water recycled is critical and is controlled by tower temperatures which are sensitive to the presence of small traces of water. In the foregoing example, when less than about 9 vol. per cent of water based on the overhead is used at a reflux ratio of 1 to 3, all of the water is vaporized in the upper part of the tower. In such cases the temperature of the phenol feed plate does not drop from the conventional operating temperature of about 234° F. and the phenol loss is high. When appreciably more than about 9 vol. per cent water is used all the temperatures throughout the extractor drop sharply from about 234° F. to 195-205° F. These figures are obtained when taking a 75% overhead yield to produce a 95% recovery of nitration grade toluene on a naphtha cut having a boiling range ranging from 175-260° F. and containing 25% toluene and the amount of the solvent used is 300 vol. per cent phenol and 10 plates are in the tower above the phenol feed plate. Where such a sharp drop in extractor temperatures, that is from 234° F. to 205° F., is obtained all of the water is not re-vaporized, some passing out the bottom of the tower, and the phenol loss in the raffinate is relatively high. When the water rate is controlled to maintain the temperature on the first few plates below the phenol feed at about 210° F. and the remaining lower plates at about 234° F., that is by using about 9 vol. per cent water, all of the water is again re-vaporized and appears with the overhead. In this case, the phenol loss is at a minimum as shown by the following data obtained when operating with a reflux ratio of 1 to 3.

TABLE I

Water injected, vol. per cent on overhead product	0	9	28
Phenol in raffinate, #/bbl.	2	0.2	3.0

As shown in the following table, the use of 9% water injection with 10 plates reduces the phenol loss to $\frac{1}{3}$ the loss with no water injection.

TABLE II

Phenol loss vs. plates

No. of plates above phenol feed	4	10	20
Phenol in raffinate, #/bbl.:			
No water injection, (1:1 external R. R.)	2.5	1.5	1.2
Water injection, 9 vol. per cent on overhead (1:3 external R. R.)	0.8	0.2	—

Although the above specifications have described only the recovery of solvents from the extractor overhead, it is also possible by means of the present invention to recover solvents from the extracts produced in the extraction process. Such solvent recovery from the extract is accomplished by feeding the extract into a distillation column where it is distilled to remove overhead the hydrocarbons concentrated in the extract while injecting water into the top of the extraction column in the same manner as already described for recovery of solvent from the extractor overhead.

While the above specifications disclose the general principles involved in this invention, what we claim specifically is as follows:

1. In the process for extracting from a mineral oil a compound selected from the group consisting of toluene and xylenes in which vapors of mineral oil are introduced to a tower and liquid phenol is introduced to the tower above the point of mineral oil introduction, the improvement which consists of introducing liquid water to the upper part of the tower above the point of phenol introduction, said water being introduced in a quantity within the range of 6 to 41 volume

percent based upon the volume of hydrocarbons withdrawn as overhead product to form a constant boiling mixture with the hydrocarbons withdrawn overhead and said quantity being such that liquid water passes downwardly in the tower but is vaporized before reaching the bottom of the tower.

2. The process for extracting toluene from mineral oil in which vapors of mineral oil are introduced to a tower and liquid phenol is introduced to the tower above the point of mineral oil introduction, the improvement which consists of introducing liquid water to the upper part of the tower above the point of phenol introduction, said water being introduced in a quantity within the range of 6 to 12 volume percent based upon the volume of hydrocarbons withdrawn as overhead product to form a constant boiling mixture with the hydrocarbons withdrawn overhead and said quantity being such that liquid water passes downwardly in the tower but is vaporized before reaching the bottom of the tower.

3. The process for extracting toluene from mineral oil in which vapors of mineral oil are introduced to a tower and liquid phenol is introduced to the tower above the point of mineral oil introduction, the improvement which consists of introducing liquid water to the upper part of the tower above the point of phenol introduction, said water being introduced in a quantity of about 9 volume percent based upon

the volume of hydrocarbons withdrawn as overhead product to form a constant boiling mixture with the hydrocarbons withdrawn overhead and said quantity being such that liquid water passes downwardly in the tower but is vaporized before reaching the bottom of the tower.

4. The process for extracting xylenes from mineral oil in which vapors of mineral oil are introduced to a tower and liquid phenol is introduced to the tower above the point of mineral oil introduction, the improvement which consists of introducing liquid water to the upper part of the tower above the point of phenol introduction, said water being introduced in a quantity within the range of 25 to 41 volume percent based upon the volume of hydrocarbons withdrawn as overhead product to form a constant boiling mixture with the hydrocarbons withdrawn overhead and said quantity being such that liquid water passes

downwardly in the tower but is vaporized before reaching the bottom of the tower.
